UNITED STATES PATENT OFFICE.

GUSTAV KNOCHENHAUER, OF SCHAALA, GERMANY.

LIGHT OR GLAZED FRAME FOR HOTBEDS, FORCING-FRAMES, &c.

SPECIFICATION forming part of Letters Patent No. 723,163, dated March 17, 1903.

Application filed October 29, 1902. Serial No. 129,278. (No model.)

To all whom it may concern:

Be it known that I, GUSTAV KNOCHENHAUER, gardner, a subject of the Prince of Schwarzburg-Rudolstadt, residing at Schaala, near Rudolstadt i. Th., in the dominion of the Prince of Schwarzburg-Rudolstadt, German Empire, have invented certain new and useful Improvements in or Relating to Lights or Glazed Frames for Hotbeds, Forcing-Frames, and the Like, of which the following is a specification.

In the construction of hotbed or like lights with removable parts, as described in my previous patent, Specification No. 707,932, of 15 August 26, 1902, the wooden longitudinal side bars of the frame and the wooden longitudinal middle bars are removably secured at their upper and lower ends between metal bars by screw-bolts in an easily-detachable 20 manner, while the spaces between the metal bars and the longitudinal bars are filled with blocks of wood detachably secured by screws to the under metal bars and with these bars forming the cross-bars of the frame.

25 In the accompanying drawings, Figure 1 shows an improved light or sash in longitudinal section. Fig. 2 is a top plan view of the same, partly in section; and Fig. 3 shows a cross-section of the window.

30 My invention relates to an improvement on the construction above described; and it consists in doing away with the metal bars and the whole of the vertical screw-bolts without in any way affecting the easy removal of the 35 single parts. Instead of the omitted parts horizontal screw-bolts 3^a are used, extending through the upper and lower ends of the longitudinal sides of the frame 1 and of the intermediate longitudinal bars 2, as well as 40 through the filling-blocks 4, with their heads y and nuts z being embedded in the longitudinal parts 1 of the frame. In this manner the window - frame is rendered perfectly smooth and flat on the outside and no metallic 45 parts except the screws y and nuts z can be seen. In order to allow broken panes to be

removed and renewed without the necessity of interfering with the bars 1 and 2, the upper blocks 4 are made in two parts, the upper parts 4^a being detachably connected by 50 screws s to the lower parts 4. When it is required to replace a broken pane, it is only necessary to remove the corresponding upper part 4^a of the upper block 4 by loosening its screws s, after which the glass can be removed from the top. After insertion of the new glass the detached parts 4^a and s are put back in their places. Handles 9 can be directly secured to the longitudinal bars 2.

Having now particularly described and ascertained the nature of my said invention and in what manner the same is to be performed, I declare that what I claim is—

In a frame for hotbeds and the like, a pair of side bars and a plurality of intermediate 65 bars extending longitudinally of said frame, each of said side bars having a longitudinal groove in its inner side, and each of said intermediate bars having two longitudinal grooves therein, a plurality of transparent 70 plates mounted end to end in said grooves and retained in position by clamps, a plurality of filling-blocks arranged transversely between the ends of said side and intermediate bars, horizontal bolts passing transversely 75 through said side and intermediate bars and longitudinally through said filling-blocks, the ends of said bolts being countersunk in said side bars, and a detachable section secured to each of the filling-blocks at one end of said 80 frame, the lower corner of each section being cut away to receive the upper edge of the adjacent transparent plate, substantially as described.

In testimony whereof I have hereunto set 85 my hand in presence of two subscribing witnesses.

GUSTAV KNOCHENHAUER.
